(57) **CLAIM**

The ornamental design for a coupling bracket for an automatic vehicle locator housing, as shown and described.

DESCRIPTION

FIG. 1 is a right front perspective view of the coupling bracket for an automatic vehicle locator housing comprising the present invention;

FIG. 2 is a top plan view thereof;

FIG. 3 is a bottom plan view thereof;

FIG. 4 is a front elevational view thereof;

FIG. 5 is a rear elevational view thereof;

FIG. 6 is a right elevational view thereof; and,

FIG. 7 is a left elevational view thereof.

The broken lines are included for the purpose of illustrating boundaries and form no part of the claimed design.
